UNITED STATES PATENT OFFICE.

HOWARD M. DUDLEY, OF PHILADELPHIA, PENNSYLVANIA.

FIBER-TREATING DEVICE.

1,304,863.

Specification of Letters Patent.

Patented May 27, 1919.

Application filed June 19, 1918. Serial No. 240,844.

To all whom it may concern:

Be it known that I, HOWARD M. DUDLEY, a citizen of the United States, residing in the city of Philadelphia, county of Philadelphia 5 and State of Pennsylvania, have invented certain new and useful Improvements in Fiber-Treating Devices, of which the following is a full, clear, and exact specification.

My invention relates to dyeing devices and 10 refers particularly to devices suitable for the dyeing or treating with liquids of wound fiber forms, such as warp balls, cops, etc.

The successful dyeing of wound fibers is dependent upon the equal and uniform passage 15 of the dye liquor through the wound fiber mass and my invention presents a device whereby this may be readily and economically accomplished.

One of the objects of my invention is a 20 foraminous device around which the fiber is wound.

Another object of my invention is a device 25 in which the dyeing liquid may be caused to pass evenly and uniformly through the device upon which the fiber is wound, and hence evenly and uniformly through the fiber wound thereon.

Another object of my invention is a foraminous device upon which the fiber is 30 wound and which will allow the compression of a series of such wound fibers and the uniform passage of a liquid therethrough.

Another object of my invention is a device 35 in which the wound fiber after compression will be held in a fixed position free from disturbance during the passage of the liquid therethrough.

These and other objects of my invention 40 will be evident upon a consideration of the specification and drawings.

As each individual warp ball, cop, or similar form contains only a limited length of fiber, it is essential that a number of such forms be treated simultaneously in order 45 that the operation may be economical, and as the passage of a liquid through such a fiber mass in one direction only is liable to form liquid passages through which the liquid passes more freely than through the other portions, it is advantageous to employ 50 a device which will allow of the passage of such liquid in reverse directions through the fiber mass.

My invention discloses a device whereby 55 these advantageous results may be obtained,

and comprises broadly a foraminous spindle with compressible and extensible sides, within which spindle is a hollow foraminous core capable of evenly diffusing a liquid through the foraminous spindle. 60

In the accompanying drawings illustrating modifications of my device, similar parts are designated by similar numerals.

Figure 1 is a vertical cross-section of one form of my device inclosed in a dyeing receptacle. 65

Fig. 2 is a top plan view of my device with the fiber wound thereon.

Fig. 3 is a section through the line 3—3 of Fig. 2 showing two foraminous spindles and 70 cores.

Fig. 4 is a development in elevation of the spring members and their connecting members, showing the blades in staggered position. 75

Fig. 5 is a plan development of Fig. 4.

Fig. 6 is a modified form of the spring members.

The particular form of the spindle of my invention, illustrated in the accompanying drawings, comprises a series of split spring members 10, 10, passing through openings 11, 11 in a series of bars or blades 12, 12, the holes 11, 11, being sufficiently large to allow of the free movement of the spring members 80 10, 10, therethrough, and the spring members 10, 10 are connected up in series of four to form a completed circle.

Each spring member 10 has two collars 13, 13 and two collars 14, 14 fixedly attached 90 near its two extremities. The adjacent ends of two spring members 10, 10 are slidable through openings in a connecting member 15. A spiral spring 16, surrounding each spring member 10, abuts upon the collar 13 95 and the connecting member 15.

Each blade, or bar, 12 carries a series of extended members 17, 17 to prevent the bars 12, 12 from sliding toward each other into positions less than the length of the members 17, 17. 100

The core of the device, as illustrated, comprises a hollow foraminous angular member formed by a series of plates 18, 18 having vertical openings 19, 19 in one side thereof and horizontal openings 20, 20 in the other side thereon. 105

The method of arranging the spindles and cores, and of passing liquid through them in reverse directions, is shown in Fig. 1. This 110

device comprises a dyeing chamber 21 formed by the hollow cylindrical member 22, having the flanges 23 and 24. The flange 24 is attached to the flange 25 of the bottom 26 by means of the screw bolts 27, 27. The bottom 26 is connected by means of the pipe 27 to a source of liquid supply and is also connected to the drain pipe 28, carrying the valve 29. The flange 23 is movably connected to the flange 30 of the top 31, by means of the wing-screw bolts 32, 32 which pass through openings in the flange 30 and thread within openings in the flange 23. A pipe 33 connects the top 31 with a source of liquid supply. The top 31 has an annular partition 34 which is extended inwardly into the stepped member 35, 36, 37. The annular hollow step 35 forms a tubular opening 38. The step 36 has two inwardly extended members 39 and 40 spaced from each other and forming a recess 41. The top 31 also contains an extended annular member 42 capable of close engagement with the inner face of the tubular member 22 and slideable thereon.

Integral with the lower portion of the interior of the cylinder 22 is an annular member 43 and its supporting members 44, 44. The member 38 has the two inwardly extended members 45 and 46 spaced from each other and forming the recess 47.

The operation of the device is as follows:—

A series of spindles is wound with the fiber 100, 100, a core is then placed within the dyeing receptacle, the outer face of the lower portion of which abuts tightly upon the angular inner face of the member 45, forming a tight joint therewith. A series of wound spindles is then placed within the dyeing chamber and around the core, the bars or blades 12, 12 of adjacent spindles being staggered with respect to each other and the lower bars or blades 12, 12 of the lower spindle being situated within the recess 47. The top 31 is then placed upon the device, the upper bars or blades of the upper spindle being situated within the recess 41.

The top 31 is then moved inwardly by means of the wing screw bolts 32, 32. By this means the member 37 presses downwardly upon the top wound fiber, thus compressing all of the wound fibers within the dyeing chamber, the annular member 42 making a tight joint within the cylindrical member 22.

As the fiber is thus compressed, it is forced against the bars or blades 12, 12 which are held tightly thereagainst by means of the springs 10, 10, thus holding the fiber free from movement during the dyeing operation. A dye liquor is then forced through the pipe 57 and thus passes through the bottom 26, the dyeing chamber 21, the wound fiber 100, the foraminous spindle into the interior of the foraminous core from which

it passes through the tubular member 38 into the top 31, and through the pipe 33 for continuous circulation.

If the flow of liquid be reversed, it will pass through the pipe 33 into the top 31 and thence through the tubular member 38 into the interior of the core, and thence outwardly through the foraminous core, the foraminous spindle and the wound fiber into the receptacle 21 from which it passes through the bottom 26 and the pipe 57 for continuous circulation.

It is to be noted that the construction of the foraminous core is of such a character as to allow the liquid passing therethrough to be impinged equally and evenly over the inner surface of the wound fibers and that the construction of the spindle is such as to allow this equal and uniform impinging of the liquid to be unimpeded, thus allowing the circulation of the liquid to be even and uniform through all portions of the various wound fibers.

In the modification shown in Fig. 6, the spring members 10, 10 have their ends bent into the form of a loop 50, the straight portion of each spring member being slideable through the loop of the adjacent spring member.

I do not limit myself to the particular size, shape, number or arrangement of parts as described and shown, all of which may be varied without going beyond the scope of my invention as described and claimed.

What I claim is:—

1. In a fiber treating device, in combination, a series of spaced members having openings therethrough and a series of split springs passing through said openings and supporting said members.

2. In a fiber treating device, in combination, a series of spaced bars having openings therethrough and a series of split springs passing through said openings and supporting the bars.

3. In a fiber treating device, in combination, a hollow foraminous core, a foraminous spindle spaced from the core and comprising a series of split springs carrying a series of spaced members.

4. In a fiber treating device, in combination, a hollow foraminous core, a foraminous spindle spaced from the core and comprising a series of split springs carrying a series of spaced bars.

5. In a fiber treating device, in combination, an angular hollow foraminous core, a foraminous spindle spaced from the core and comprising a series of split springs carrying a series of spaced members.

6. In a fiber treating device, in combination, an angular hollow foraminous core, a foraminous spindle spaced from the core and comprising a series of split springs carrying a series of spaced bars.

7. In a fiber treating device, in combination, a hollow foraminous core, a foraminous spindle spaced from the core and comprising a series of spaced members having openings therethrough and a series of split springs passing through said openings and supporting said members.

8. In a fiber treating device, in combination, a hollow foraminous core, a foraminous

spindle spaced from the core and comprising a series of spaced bars having openings therethrough and a series of split springs passing through said openings and supporting said bars.

Signed at New York, in the county of New York and State of New York, this 12th day of June, 1918.

HOWARD M. DUDLEY.
